UNITED STATES PATENT OFFICE.

HARRY L. BRESLAW, OF NEW YORK, N. Y.

FUR CAP.

1,332,883.

Specification of Letters Patent.

Patented Mar. 9, 1920.

Application filed March 20, 1918. Serial No. 223,551.

To all whom it may concern:

Be it known that I, HARRY L. BRESLAW, a citizen of the United States, and a resident of New York, in the county of New 5 York and State of New York, have invented a certain new and useful Improvement in Fur Caps, of which the following is a full, clear, and exact specification.

This invention relates more particularly 10 to a class of head wear.

My invention has for its object primarily to provide a fur cap designed to be worn by a person whereby the ears and back of the head of the wearer will be effectually protected during cold weather, and which is of a form adapted to be slidably adjusted to snugly fit over as well as to entirely cover the ears and base of the back of the head without tending to protrude laterally from 15 these parts of the wearer, besides overcoming the liability of soiling and prematurely damaging the exposed part of the band by contact with the head of the wearer as is incident to types of caps made with bands 20 adapted to be turned-up and turned-down. The invention consists mainly of a crown member which may be of any well-known or preferred form, and on the exterior of the crown member at its marginal edge is a movable band member of fur. To the crown 25 member at its marginal edge is connected a flexible slide element which is also attached to the band member in a manner so that the band member may be slidably guided back 30 and forth to extensible positions below the marginal edge of the crown member.

A further object of the invention is to provide a fur cap of a simple, efficient and durable construction, and which is susceptible 35 of being made in various shapes and sizes.

A practical embodiment of the invention is represented in the accompanying drawing forming a part of this specification in which similar characters of reference indicate corresponding parts in all the views, the said invention being more fully described hereinafter, and then pointed out in the claims at the end of the description.

In the drawing, Figure 1 is an elevation 45 of one form of fur cap embodying my invention showing the band of the cap adjusted to cover the ears and lower part of the back of the head of a person.

Fig. 2 is an elevation of the cap with its 50 parts arranged in their normal positions.

Fig. 3 is a detail sectional view taken on the line 3—3 of Fig 2.

Fig. 4 is a detail sectional view taken on the line 4—4 of Fig. 1, and

Fig. 5 is an enlarged elevation of the slide 60 element used in the cap.

The cap has a fur crown member 10 which may be of the usual or any preferred shape and size for being removably worn by a person on the head in the fashion common 65 to wearing the usual styles of caps. Extending from the marginal edge of the front part of the crown member 10 may be a fur vizor 11 which may also be of the ordinary or any preferred type for shading and protecting the forehead and eyes of the wearer.

Movably fitting closely the crown member 10 on the exterior of the portion at its marginal edge is a band member 12, which may be of a length so that its ends terminate in 75 proximity to the vizor 11, and this band member may be of any suitable width, though the member is usually made sufficiently wide that when adjustably arranged to extend below the crown member the back 80 of the head and the ears of the wearer will be completely covered. This band member is also made of fur in a manner whereby its pile is exposed on both of its surfaces. This is accomplished by making the band 85 member of a strip of the required length, and then overlapping both of its lengthwise edge portions each corresponding to approximately one-quarter the width of the strip so that the edges meet centrally of the strip. 90 The band member 12 may be of any desired width, besides being of any suitable shape, though the ends of the band member are preferably tapered, as 13 and 14. This band member, as shown, is of a length 95 so that its ends are spaced apart at the front of the crown member, and the tapered ends 13 and 14 of the band member may be yieldingly fastened together by means of one or more strips of elastic thread or rubber, as 100 14^a. This elastic strip is disposed cross-wise of the front of the crown member above the vizor 11, and by the use of the strip in this manner the band member when lowered downwardly from the free edge of the crown member will tend to be guided inwardly and under the crown member as shown in Fig. 4, so as to closely hug the head and ears of the wearer of the cap.

In order to allow the band member 12 to 110

be slidably adjusted upwardly and downwardly to and from extensible positions below the edge of the crown member 10, I provide a slide element, as 15. The slide element may be made of cloth or other flexible material, and this element is substantially similar in length to the length of the band member 12. The upper and lower edges of the slide element are preferably 5 rectilinear, while the ends of the element are cut away on an incline or tapered, as at 16 and 17, from the lower edge of the element to its upper edge. The lower edge of the slide element 15 including the inclined parts 16 and 17 are stitched or otherwise secured, as at 18, to both of the lengthwise overlapping edges of the band member 12, while the upper lengthwise edge of the slide element is also stitched or otherwise attached, 10 as at 21, to the edge of the crown member 10 of the cap.

The flexible slide element is of a width whereby the band is normally positioned on the crown member of the cap so that the 15 lower edges of the crown member and the band member are alined with each other. The cap is applied to the head of a person in the usual fashion so that the vizor 11 is above the eyes. When it is desired to 20 protect the ears and base of the back of the head of the wearer the band member 12 is adjustably guided downwardly below the crown member and by making the slide element 15 of the required width the ears 25 and lower part of the back of the head of the wearer will be covered by one-half of the fur part of the band member. By making the band member and the slide element with tapered ends the band member when 30 adjusted in this manner will tend to be drawn inwardly toward the center of the concavity of the crown member, and in turn the band member will movably fit 35 closely to the ears and back of the head of the wearer. Moreover, by making the band member in this fashion it will not be required to be turned upwardly and downwardly with respect to the crown member 40 as is incident to fur caps of ordinary styles, and the liability of soiling and prematurely 45 damaging the exposed part of the band member by contact with the head of the person will thereby be avoided.

In the foregoing description, I have embodied the preferred form of my invention, 50 but I do not wish to be understood as limiting myself thereto, as I am aware that modifications may be made therein without de-

parting from the principle or sacrificing any of the advantages of this invention, therefore I reserve to myself the right to make such changes as fairly fall within the scope thereof.

Having thus described my invention, I claim as new and desire to secure by Letters Patent:—

1. A cap comprising a crown member, a band member movably arranged partially around the crown member at its marginal edge and having tapered ends, said band member being of a length and arranged so that its tapered ends are spaced apart at the sides of the crown member near the front of the latter, a tapered flexible strip having one of its lengthwise edges connected to the edge of the crown member and having its second lengthwise edge attached substantially centrally to the band member whereby the band member may be slidably adjusted above and below the marginal edge of the crown member, and means yieldingly connecting the tapered ends of the band member to pull the latter inwardly and under the crown member when the band member is adjusted below the crown member.

2. A cap comprising a fur crown member, a fur band member with overlapped edges so that the fur is exposed on both surfaces, said band member being movably arranged partially around the crown member at its marginal edge and having tapered ends as well as being of a length and arranged so that its tapered ends are spaced apart at the sides of the crown member near the front of the latter, a tapered flexible strip having one of its lengthwise edges connected to the edge of the crown member and having its second lengthwise edge attached to the edges of the overlapped parts lengthwise of the band member whereby the band member may be slidably adjusted above and below the marginal edge of the crown member, and an elastic strip connecting the tapered ends of the band member and disposed crosswise of the front of the crown member to pull the band member inwardly and under the crown member when the band member is adjusted below the crown member.

This specification signed and witnessed 110 this 19th day of March A. D. 1918.

HARRY L. BRESLAW.
